(57) **CLAIM**

The ornamental design for a electrosurgical cutting blade, as shown and described.

DESCRIPTION

FIG. 1 is a top plan view of an electrosurgical cutting blade showing my new design.

FIG. 2 is side elevational view thereof.

FIG. 3 is a distal end elevational view thereof; and,

FIG. 4 is a perspective view thereof.

Any indicia, including but not limited to words and symbols, shown on the accompanying drawings form no part of the claimed design. Broken lines are included for the purpose of illustrating portions of the electrosurgical cutting blade that form no part of the claimed design.

1 Claim, 4 Drawing Sheets

FIG. 2

FIG. 3

FIG. 4
